(21) Appl. No.: **29/318,637**

(57) **CLAIM**

(22) Filed: **May 23, 2008**

We claim the ornamental design for a microwave oven, as shown and described.

(30) **Foreign Application Priority Data**

Nov. 27, 2007 (KR) 30-2007-0049272

DESCRIPTION

(51) **LOC (9) Cl.** **07-02**

FIG. 1 is a perspective view of a microwave oven showing the new design;

(52) **U.S. Cl.** **D7/351**

FIG. 2 is a front elevation view thereof;

(58) **Field of Classification Search** .... D7/350.1, D7/350.3, 350.4, 351, 402, 405; 126/19 M, 126/275 E; 219/756–758, 679, 680, 725, 219/727, 734, 435; 99/DIG. 14

FIG. 3 is a rear elevation view thereof;

See application file for complete search history.

FIG. 4 is a left-side elevation view thereof;

(56) **References Cited**

FIG. 5 is a right-side elevation view thereof;

U.S. PATENT DOCUMENTS

FIG. 6 is a top plan view thereof; and,

D522,800 S * 6/2006 Lee et al. D7/351

FIG. 7 is a bottom plan view thereof.
